UNITED STATES PATENT OFFICE.

FREDRICK J. FURMAN, OF GENEVA, NEW YORK, ASSIGNOR TO THE
HIERENDEEN MANUFACTURING COMPANY, OF SAME PLACE.

GENERATOR.

SPECIFICATION forming part of Letters Patent No. 617,092, dated January 3, 1899.

Application filed February 25, 1898. Serial No. 671,674. (No model.)

To all whom it may concern:

Be it known that I, FREDRICK J. FURMAN, of Geneva, in the county of Ontario, in the State of New York, have invented new and 5 useful Improvements in Generators, of which the following, taken in connection with the accompanying drawings, is a full, clear, and exact description.

My invention relates to improvements in 10 generators particularly applicable for heating purposes, and has for its object the production of a simple and practical construction which is economically manufactured and assembled and is highly efficient in use; and to 15 this end it consists in the combination, construction, and arrangement of the component parts of a generator, as hereinafter fully described, and pointed out in the claims.

In describing this invention reference is 20 had to the accompanying drawings, forming part of this specification, in which like letters indicate corresponding parts in all the views.

Figure 1 is a perspective of my improved generator, the ash-door being shown by dotted lines. Figs. 2 and 3 are respectively vertical and horizontal sectional views taken on lines 2 2 and 3 3, Fig. 1, the smoke-conduit projecting from the rear section being omitted in Fig. 2. Figs. 4 and 5 are perspective 25 views of the opposite faces of the front section of my improved generator. Fig. 6 is a perspective view of one of the intermediate sections of said generator inclosing the combustion-chamber. Figs. 7 and 8 are perspective 30 views of opposite faces of the section forming the rear wall of the combustion-chamber. Fig. 9 is a perspective view of the section arranged at the rear of the section seen in Figs. 7 and 8. Figs. 10 and 11 are opposite face views of the rear section of my 35 generator.

This improved generator preferably consists of a series of upright sections A A' A² A³ A⁴ A⁵ A⁶, arranged one in advance of the 40 other and preferably constructed so as to form the outer casing or shell of the generator and to inclose its combustion-chamber A⁷, ash-pit A⁸, heating-chambers, and smoke-conduits. The sections A A' A² A³ A⁴ A⁵ A⁶ 45 are preferably formed with substantially up-

right and horizontal fluid-containing chambers a a', alined with each other and provided with fluid-passages a² a³, which generally extend through the front and rear walls of the lower ends of the chambers a and the central 55 portions of the chambers a' and receive suitable bolts B for securing said sections together. The chambers a are usually comparatively narrow and extend upwardly from a plane substantially coincident with that of 60 the bottom of the combustion-chamber to a plane above said chamber. It is obvious, however, that the chambers a may extend upwardly from a higher or lower plane, if desired. The chambers a' are preferably continuous from end to end, are connected at 65 their opposite extremities to the upper ends of the substantially upright chambers a, and are provided with upwardly-extending central portions a⁴. The lower portions of all 70 the chambers a' usually decrease in thickness toward their bottom edges, extend downwardly between the upright chambers a, and communicate with the inner sides of the chambers a, and the lower portions of the chambers a' of the sections A A' A² A³ are formed 75 with downturned extremities a⁵. The opposite faces of the lower portions of the fluid-containing chambers a' of the sections A' A² A³ A⁴ A⁵ and the inner faces of the corresponding portions of the chambers a' of the sections A A⁶ are generally provided with substantially upright corrugations a⁶ for presenting a large amount of heating-surface to 80 the products of combustion impinging thereagainst. Said faces of the sections A A' A² A³ are also generally provided with projecting lengthwise surfaces a⁷, arranged one above the other for additionally increasing the heating-surface presented to said products of combustion. It is obvious, however, that the corrugations a⁶ and the surfaces a⁷ may be dispensed with, if desired. 85

In the preferable construction of my generator the sections A A' A² A³ A⁴ inclose the 90 combustion-chamber A⁷ and the ash-pit A⁸, and the sections A⁵ A⁶ are arranged at the rear of said combustion-chamber and ash-pit. The fluid-containing chambers a of the sections A A' A² A³ A⁴ are therefore preferably 95 100

arranged at opposite sides of the combustion-chamber A⁷ for forming the side walls thereof, and the lower portions of the chambers a' of the sections A A⁴ are extended downwardly 5 beneath the corresponding portions of the sections A' A² A³ for forming the front and rear walls of said chamber A⁷. The lower portion of the chamber a' of the section A is generally formed thinner than the chambers a of 10 said section in order that its rear face may be somewhat in advance of the corresponding faces of said chambers a. The lower portion of said chamber a' is also formed with an opening a⁸, which permits the entrance of fuel 15 within the combustion-chamber A⁷, and is closed by a suitable door A⁹. The side walls of the sections A A' A² A³ A⁴ usually extend downwardly beneath their chambers a for inclosing the ash-pit A⁸, which may be provided with a suitable inlet-opening a¹⁰ and a door a¹¹.

The sections A A' A² A³ A⁴ are preferably provided with suitable flues A⁹ and fire-passages A¹⁰. The flues A⁹ generally consist of 25 upwardly-elongated passages, which extend through the front and rear faces of the sections A A' A² A³ A⁴ from points at opposite sides of the combustion-chamber A⁷ to points above said chamber. The fire-passages A¹⁰ 30 extend laterally from the portions of the inner sides of the chambers a of the sections A A' A² A³ A⁴, forming the upright sides of the combustion-chamber, and communicate at intervals with the inner sides of the flues 35 A⁹. These fire-passages preferably consist of grooves or cut-outs, which are provided in the adjacent faces of the sections A A' A² A³ A⁴, are alined with the spaces between the lower portions of the chambers a' of said sections, and are usually formed of unequal 40 width, being generally increased gradually in width toward the front end of the combustion-chamber A⁷ in order to equalize the draft from all portions of the combustion-chamber. 45

The sections A⁵ A⁶, arranged at the rear of the combustion-chamber A⁷, serve to materially cool the products of combustion before their escape from my improved generator. The substantially upright fluid-containing 50 chambers a of these sections A⁵ A⁶ are usually somewhat narrower than the corresponding chambers of the sections A A' A² A³ A⁴, and the lower portions of the fluid-containing chambers a' of the sections A⁵ A⁶ are extended 55 downwardly to substantially the same plane as the corresponding portion of the chamber a' of the section A⁴. As previously stated, the lower portions of the chambers a' of the sections A⁵ A⁶ decrease in width to 60 ward their lower edges, and consequently substantially upright smoke-passages A¹¹ are interposed between the adjacent surfaces of the sections A⁴ A⁵ A⁶. It is obvious, however, that the smoke-passages may be formed 65 by suitable grooves in the adjacent faces of the sections A⁴ A⁵ A⁶. The upper and lower ends of the upright smoke-passages A¹¹ are

generally connected by substantially horizontal passages A¹² A¹³ in the intermediate and lower portions of the section A⁵. The 70 passage A¹² may be closed by a suitable damper A¹⁴, and the passage A¹³ is normally open. The section A⁶ is usually provided with a smoke-passage A¹⁵, extending from front to rear therethrough in alinement with the passage A¹² and discharging into a suitable smoke-conduit A¹⁶.

From the foregoing description it will be understood that the chambers a a' of the sections A A' A² A³ A⁴ A⁵ A⁶ constitute the heating-chambers of my improved generator and that the flues A⁹, fire-passages A¹⁰, and smoke-passages A¹¹ A¹² A¹³ A¹⁵ form the conduits or passages for the products of combustion. The steam or water heated within said heating-chambers escapes through suitable conduits A¹⁷, and is returned to said chambers, together with any additional feed-water, by conduits A¹⁸, which preferably discharge into the lower portion of the chamber a' of the 90 section A⁶. The circulation of the water in my improved generator is particularly positive and effective, as the paths of the water are upright and short and as there is an up-and-down circulation on each side of the combustion-chamber. The products of combustion 95 impinge directly against the lower portions of the chambers a', which presents a large amount of surface to said products of combustion and divide the same into thin sheets for causing 100 a great amount of heat to be imparted to the adjacent water. Said products of combustion are somewhat retarded in their onward movement by the spaces between the lower portions of the chambers a', but finally pass laterally from the combustion-chamber A⁷ and said spaces in thin sheets through the fire-passages A¹⁰ and into the flues A⁹ and smoke-passages A¹¹, whence they escape through the 105 passages A¹² A¹⁵ when the damper A¹⁴ is open or through the passages A¹³ A¹⁵ when said damper is closed. There are comparatively few horizontal surfaces in my improved generator for the accumulation of soot, and the products of combustion within said generator are divided 110 into thin sheets, escape at substantially uniform speed from all portions of the combustion-chamber, and before their exit pass along surfaces cooled by the incoming water. The 115 efficiency of said generator is therefore particularly high.

The construction and operation of my improved generator will now be readily understood upon reference to the foregoing description and the accompanying drawings, and it 125 will be obvious that considerable change may be made in the detail construction and arrangement of the parts of said generator without departing from the spirit of my invention.

Having thus fully described my invention, 130 what I claim as new, and desire to secure by Letters Patent, is—

1. A generator comprising upright sections arranged one in advance of the other, a num-

ber of the sections being each formed with substantially upright chambers at opposite sides of the combustion-chamber, and a continuous substantially horizontal chamber communicating at its opposite extremities with the upper ends of the upright chambers and having its lower portion decreased in thickness toward its bottom edge and provided with substantially upright corrugations and substantially lengthwise surfaces projecting from its opposite faces in planes arranged one above the other, substantially as set forth.

2. A generator comprising upright sections arranged one in advance of the other, a number of the sections being each formed with substantially upright chambers at opposite sides of the combustion-chamber, and a continuous substantially horizontal chamber communicating at its opposite extremities with the upper ends of the upright chambers and having its central portion extended upwardly and its lower portion extended downwardly between the upright chambers and formed with downturned extremities communicating with the inner sides of said upright chambers, said lower portion being decreased in thickness toward its bottom edge and provided with substantially upright corrugations, and substantially lengthwise surfaces projecting from its opposite faces in planes arranged one above the other substantially as and for the purpose described.

3. A generator comprising upright sections arranged one in advance of the other, a number of the sections being each formed with substantially upright chambers at opposite sides of the combustion-chamber connected at their upper ends, said chambers being provided with flues extending through their front and rear faces, and fire-passages projecting laterally from the flues for conducting the products of combustion thereto, substantially as specified.

4. A generator comprising upright sections arranged one in advance of the other, a number of the sections being each formed with substantially upright chambers at opposite sides of the combustion-chamber provided with flues extending through their front and rear faces, and fire-passages projecting laterally from the inner sides of the flues for conducting the products of combustion thereto, and a substantially horizontal chamber communicating at its opposite extremities with the upper ends of the upright chambers and having its lower portion decreased in thickness toward its bottom edge, substantially as and for the purpose described.

5. A generator comprising upright sections arranged one in advance of the other, a number of the sections being each formed with substantially upright chambers at opposite sides of the combustion-chamber provided with flues extending through their front and rear faces, fire-passages projecting laterally from the inner sides of the flues for conducting the products of combustion thereto, and a sub-

stantially horizontal chamber communicating at its opposite extremities with the upper ends of the upright chambers and having its lower portion extended downwardly between the fire-passages and provided with substantially lengthwise surfaces projecting from its opposite faces in planes arranged one above the other, substantially as and for the purpose set forth.

6. A generator comprising upright sections arranged one in advance of the other, a number of the sections being each formed with substantially upright chambers at opposite sides of the combustion-chamber provided with flues extending through their front and rear faces, fire-passages projecting laterally from the inner sides of the flues for conducting the products of combustion thereto, and a substantially horizontal chamber communicating at its opposite extremities with the upper ends of the upright chambers and having its lower portion extended downwardly between the fire-passages and provided with substantially upright corrugations, substantially as and for the purpose described.

7. A generator comprising upright sections arranged one in advance of the other, a number of the sections being each formed with substantially upright chambers at opposite sides of the combustion-chamber provided with flues extending through their front and rear faces, fire-passages projecting laterally from the inner sides of the flues for conducting the products of combustion thereto, and a substantially horizontal chamber communicating at its opposite extremities with the upper ends of the upright chambers and having its lower portion extended downwardly between the fire-passages and provided with substantially upright corrugations and substantially lengthwise surfaces projecting from its opposite faces in planes arranged one above the other, substantially as and for the purpose specified.

8. A generator comprising upright sections arranged one in advance of the other, a number of the sections being each formed with substantially upright chambers at opposite sides of the combustion-chamber connected at their upper ends, said chambers being provided with elongated upright flues extending through their front and rear faces at opposite sides of the combustion-chamber, and having their front and rear faces formed with fire-passages projecting laterally from the inner sides of the flues through the upright sides of the combustion-chamber for conducting the products of combustion to said flues, substantially as and for the purpose set forth.

9. A generator comprising upright sections arranged one in advance of the other, a number of the sections being each formed with substantially upright chambers at opposite sides of the combustion-chamber connected at their upper ends, said chambers being provided with flues extending through their front and rear faces, and fire-passages of unequal size

projecting laterally from the flues for conducting the products of combustion thereto, substantially as specified.

10. A generator comprising upright sections arranged one in advance of the other, a number of the sections being each formed with substantially upright chambers at opposite sides of the combustion-chamber provided with flues extending through their front and rear faces, and fire-passages projecting laterally from the inner sides of the flues for conducting the products of combustion thereto, and a substantially horizontal chamber communicating at its opposite extremities with the upper ends of the upright chambers and having its lower portion extended downwardly between the fire-passages, substantially as set forth.

11. A generator comprising upright sections arranged one in advance of the other, a number of the sections being each formed with substantially upright chambers at opposite sides of the combustion-chamber connected at their upper ends and provided with flues extending through their front and rear faces, fire-passages of unequal size projecting laterally from the flues for conducting the products of combustion thereto, and a substantially horizontal chamber communicating at its opposite extremities with the upper ends of the upright chambers, substantially as and for the purpose set forth.

12. A generator comprising upright sections arranged one in advance of the other, a number of the sections being each formed with substantially upright chambers at opposite sides of the combustion-chamber provided with elongated substantially upright flues extending through their front and rear faces from points at opposite sides of the combustion-chamber to points above said combustion-chamber, said chambers having their front and rear faces provided with fire-passages of unequal size projecting laterally from the inner sides of the flues for conducting the products of combustion thereto, substantially as and for the purpose specified.

13. A generator comprising upright sections arranged one in advance of the other, a number of the sections being each formed with substantially upright chambers at opposite sides of the combustion-chamber provided with elongated substantially upright flues extending through their front and rear faces from points at opposite sides of the combustion-chamber to points above said combustion-chamber, fire-passages projecting laterally from the inner sides of the elongated flues for conducting the products of combustion thereto, and a substantially horizontal chamber communicating at its opposite extremities with the upper ends of the upright chambers and having its central portion extended upwardly and its lower portion formed with downturned extremities extended between the upper ends of the fire-passages, substantially as and for the purpose set forth.

14. A generator comprising upright sections arranged one in advance of the other, a number of the sections being each formed with substantially upright chambers at opposite sides of the combustion-chamber provided with elongated substantially upright flues extending through their front and rear faces from points at opposite sides of the combustion-chamber to points above said combustion-chamber, fire-passages of unequal size projecting laterally from the flues for conducting the products of combustion thereto, and a substantially horizontal chamber communicating at its opposite extremities with the upper ends of the upright chambers, substantially as and for the purpose described.

15. A generator comprising upright sections arranged one in advance of the other, a number of the sections being each formed with substantially upright chambers at opposite sides of the combustion-chamber, and a continuous substantially horizontal chamber communicating at its opposite extremities with the upper ends of the upright chambers and having its lower portion decreased in thickness toward its bottom edge, the lower portion of the substantially horizontal chamber of one of the sections being extended downwardly beneath the lower portions of the substantially horizontal chambers of others of said sections for forming the rear wall of the combustion-chamber, substantially as and for the purpose described.

16. A generator comprising upright sections arranged one in advance of the other, a number of the sections being each formed with substantially upright chambers at opposite sides of the combustion-chamber, and a continuous substantially horizontal chamber communicating at its opposite extremities with the upper ends of the upright chambers and having its lower portion decreased in thickness toward its bottom edge, the lower portion of the substantially horizontal chamber of one of the sections being formed with substantially upright corrugations and extended downwardly beneath the lower portions of the substantially horizontal chambers of others of said sections for forming the rear wall of the combustion-chamber, substantially as and for the purpose described.

17. A generator comprising upright sections arranged one in advance of the other, a number of the sections being each formed with substantially upright chambers at opposite sides of the combustion-chamber connected at their upper ends, said chambers being provided with flues extending through their front and rear faces, and one of the sections being provided with flues extending through its front and rear faces and aligned with the former flues, fire-passages projecting laterally from the inner sides of its flues, and a water-containing chamber arranged at the rear of the fire-passages for forming the rear wall of the combustion-chamber, substantially as and for the purpose described.

18. A generator comprising upright sections arranged one in advance of the other, a number of the sections being each formed with substantially upright chambers at opposite sides of the combustion-chamber connected at their upper ends and provided with flues extending through their front and rear faces, and fire-passages projecting laterally from the flues for conducting the products of combustion thereto, and one of the sections being provided with flues extending through its front and rear faces and aligned with the former flues, fire-passages projecting laterally from the inner sides of its flues, and a water-containing chamber arranged at the rear of the fire-passages for forming the rear wall of the combustion-chamber, substantially as and for the purpose specified.

19. A generator comprising upright sections arranged one in advance of the other, a number of the sections being each formed with substantially upright chambers at opposite sides of the combustion-chamber connected at their upper ends and provided with flues extending through their front and rear faces, and fire-passages of unequal size projecting laterally from the flues for conducting the products of combustion thereto, and one of the sections being provided with flues extending through its front and rear faces and aligned with the former flues, fire-passages projecting laterally from the inner sides of its flues, and a water-containing chamber arranged at the rear of the fire-passages for forming the rear wall of the combustion-chamber, substantially as and for the purpose specified.

20. A generator comprising upright sections arranged one in advance of the other, a number of the sections being each formed with substantially upright chambers at opposite sides of the combustion-chamber provided with flues extending through their front and rear faces, fire-passages projecting laterally from the inner sides of the flues for conducting the products of combustion thereto, and a substantially horizontal chamber communicating at its opposite extremities with the upper ends of the upright chambers and having its lower portion decreased in thickness toward its bottom edge, and another of the sections being provided with flues aligned with the former flues, fire-passages extending laterally from the inner sides of the latter flues, and a substantially horizontal chamber having its lower portion extended beneath the lower portions of the substantially horizontal chambers of the former sections and arranged at the rear of the combustion-chamber for forming the rear wall of said combustion-chamber, substantially as and for the purpose specified.

21. A generator comprising upright sections arranged one in advance of the other, a number of the sections being each formed with substantially upright chambers at opposite sides of the combustion-chamber provided

with flues extending through their front and rear faces, and a continuous substantially horizontal chamber communicating at its opposite extremities with the upper ends of the upright chambers and having its lower portion decreased in thickness toward its bottom edge, one of the sections having the lower portion of its substantially horizontal chamber extended beneath the lower portions of the substantially horizontal chambers of others of said sections for forming the rear wall of the combustion-chamber, and another of the sections being formed with a water-containing chamber at the rear of the water-containing chamber of said one of the sections and a smoke-passage in front of said chamber communicating with said flues, substantially as and for the purpose described.

22. A generator comprising upright sections arranged one in advance of the other, a number of the sections being each formed with substantially upright chambers at opposite sides of the combustion-chamber connected at their upper ends and provided with flues extending through their front and rear faces, fire-passages projecting laterally from the flues for conducting the products of combustion thereto, and a continuous substantially horizontal chamber communicating at its opposite extremities with the upper ends of the upright chambers, one of the sections having the lower portion of its substantially horizontal chamber extended beneath the lower portions of the substantially horizontal chambers of others of said sections for forming the rear wall of the combustion-chamber, and another of the sections being formed with a water-containing chamber at the rear of the water-containing chamber of said one of the sections and a smoke-passage in front of said chamber communicating with said flues, substantially as and for the purpose described.

23. A generator comprising upright sections arranged one in advance of the other, a number of the sections being each formed with substantially upright chambers at opposite sides of the combustion-chamber connected at their upper ends and provided with flues extending through their front and rear faces, fire-passages of unequal size projecting laterally from the flues for conducting the products of combustion thereto, and a continuous substantially horizontal chamber communicating at its opposite extremities with the upper ends of the upright chambers, one of the sections having the lower portion of its substantially horizontal chamber extended beneath the lower portions of the substantially horizontal chambers of others of said sections for forming the rear wall of the combustion-chamber, and another of the sections being formed with a water-containing chamber at the rear of the water-containing chamber of said one of the sections, and a smoke-passage in front of said chamber communicating with said flues, substantially as and for the purpose set forth.

24. A generator comprising upright sections arranged one in advance of the other, a number of the sections being each formed with substantially upright chambers at opposite sides of the combustion-chamber provided with flues extending through their front and rear faces, and a continuous substantially horizontal chamber communicating at its opposite extremities with the upper ends of the upright chambers and having its lower portion decreased in thickness toward its bottom edge, one of the sections having the lower portion of its substantially horizontal chamber extended beneath the lower portions of the substantially horizontal chambers of others of said sections for forming the rear wall of the combustion-chamber, and others of the sections being formed with water-containing chambers at the rear of the water-containing chamber of said one of the sections, and smoke-passages interposed between said water-containing chambers and communicating with said flues, said smoke-passages being connected together at their upper and lower ends, substantially as and for the purpose described.
25. A generator comprising upright sections arranged one in advance of the other, a number of the sections being each formed with substantially upright chambers at opposite sides of the combustion-chamber con-

nected at their upper ends and provided with flues extending through their front and rear faces, fire-passages projecting laterally from the flues for conducting the products of combustion thereto, and a continuous substantially horizontal chamber communicating at its opposite extremities with the upper ends of the upright chambers, one of the sections having the lower portion of its substantially horizontal chamber extended beneath the lower portions of the substantially horizontal chambers of others of said sections for forming the rear wall of the combustion-chamber, and others of the sections being formed with water-containing chambers at the rear of the water-containing chamber of said one of the sections and smoke-passages interposed between said water-containing chambers and communicating with said flues, said smoke-passages being connected together at their upper and lower ends, substantially as and for the purpose described.

In testimony whereof I have hereunto signed my name, in the presence of two attesting witnesses, at Geneva, in the county of Ontario, in the State of New York, this 4th day of February, 1898.

FREDRICK J. FURMAN.
